UNITED STATES PATENT OFFICE

ALBERT G. STOOPS, OF TULSA, OKLAHOMA

TORPEDO SHELL

Application filed January 20, 1930. Serial No. 421,912.

My invention relates to containers and more particularly to torpedo shells or containers for holding explosives such as nitro-glycerin used for shooting sands or other formations in oil and gas wells.

In the process of shooting oil sands, or other formations, for creating a pocket or breaking and cracking up the wall structure of an oil or gas well, it is very essential that every precaution be taken to prevent premature explosion of the explosive during its descent in the well, and it is the principal object of my invention to minimize such disasters by providing non-metallic means for attaching improved tops and bottoms to shells of this type.

In some wells, drilling is continued below the depth of the oil sand and it is a further object of my invention to embody means for supporting a container at a predetermined height above the well hole bottom in order to deliver the full charge of explosives into the oil sand.

Another object of this invention is to provide tops for containers of this character, especially those of relatively small diameters, adapted to be attached to bottoms of superimposed containers, thus providing a string of explosives for wells wherein the layer of oil sand is of such thickness that the use of a single container would be impractical.

In accomplishing these and other objects of the invention, I have provided improved details of structure, the preferred forms of which are illustrated in the accompanying drawings, wherein:

Fig. 1 is a central vertical section of a well hole and casing illustrating a pair of containers being lowered into position for discharging.

Fig. 2 is a central vertical section of containers in assembled relation.

Fig. 3 is a perspective view of a container and connecting link in disassembled relation.

Fig. 4 is a cross section on the line 4—4, Fig. 2.

Referring more in detail to the drawings:

1 designates a well hole drilled through cap rock 2 and oil sand 3, and terminating in more solid formation 4, below the oil sand,

the well being lined with casing 5 supported by a shoe 6 on the cap rock 2.

In order to deliver a charge of explosives, such as nitro-glycerin, into the well for shooting the oil sand to create a pocket for the collection of oil, I provide containers 7 of improved construction, each including a tubular shell or body member 8 of non-metallic material such as compressed paper pulp or the like.

Mounted within the upper end of the shell is a closure member 9, preferably of molded paper pulp, treated with an impregnating solution to give it strength and to make it resistant to oil, water and dilute acids. The closure member comprises a cylindrical portion 10 adapted to engage the inner wall of the tube, and has an outwardly directed flange 11 on its outer end to seat on the end of the shell. The closure member is further provided with a funnel-shaped opening 12 and with a counterbored recess 13, the lower end 14 being formed with a conical flange 15 to facilitate insertion of the top into the shell. Diametrically opposed notches 16 in the flange and continuing as grooves 17 in the cylindrical member 10, terminate in lateral openings 18 adjacent the lower end of the closure member for receiving the hooks 19 of a bail 20.

In order to securely mount a closure member in a shell, a coat of cement is applied to the outer wall of the closure member before it is inserted in the shell. Holes 21 are then drilled transversely and preferably in staggered relation through the wall of the shell and the counterbored portion 13 of the top for receiving pins 22, preferably of wood.

Mounted in the lower end of the shell is a bottom member 23, also molded of treated paper pulp, and comprising a reduced cylindrical inner end 24 having a closed wall 25 and a conical outer end 26 provided with a concentric opening 27. The closure member is secured in the shell by cement and pins 22' in like manner as the top member previously described. The concentric opening 27 is adapted to receive the conical upper end 28 of a cylindrical anchoring tip 29 having a closed lower end wall 30, a non-metallic cross

pin 31 being extended through the conical outer end and anchoring tip.

The conical outer end 26 and the end wall 30 are perforated as indicated at 32, for permitting equalizing of internal and external pressures to prevent float action of the hollow closure member and anchoring tip. The opening 27 is further adapted to receive the upper end 33 of a conical end tip 34 so that either the end tip or the anchoring tip, each 10 formed of paper pulp or like material, may be mounted in the closure member as occasion demands.

With the use of the anchoring tip, a cylindrical end 35 of any desired length comprising a pipe or the like, of light material, may be attached to the lower end of the shell for supporting the container at a predetermined elevation above the bottom of the well hole.

20 The depth of the oil sand is frequently so great that it is necessary to employ a series of superimposed containers in order to shoot the oil sand throughout its depth.

When containers of large diameters are 25 used they are individually lowered into the well hole and permitted to rest upon each other. However, with containers of smaller diameters, this is impractical for obvious reasons, and for this purpose I have provided 30 a hook 36 for attaching the lower end of a container to the bail of the next lower container. The hook preferably comprises a heavy wire extended through aligning openings 37 in the bottom member 23, the arms 38 35 of the hook being bent downwardly adjacent the conical end wall of the closure member and registering wall of the end tip 34, and terminating in overlapping hook portions 39 for engaging the bail of a lower container.

40 A cross bar 40 extended through openings 41 in the end tip is welded at its ends to the arms 38 of the hook, as indicated at 42.

Various means may be employed for lowering the containers to the bottom of the well 45 hole, but I have illustrated for this purpose a cable 43 attached to the bail of the upper container by an open hook 44.

Assuming a torpedo to be assembled and 50 constructed as described, the process for connecting and lowering the containers into the bore of a well would be as follows:

55 After determining the depth at which the shot is to be discharged above the bottom of the well, a pipe of corresponding length is attached by an anchoring tip to the lower closure member. If, however, it is desired to explode the charge at the bottom of the hole, an end tip is mounted in the closure 60 member instead. A sufficient number of containers, if of small diameters, are then linked together to extend substantially throughout the depth of the oil sand and the string of containers is filled with a charge of explosives and lowered into the well by hook and

cable, the contents being discharged as in common practice.

Due to the method of attaching the upper and lower closure members to the shell, and to the inset position of the bail, the danger of heat incident to friction, or of sparks created by this type of container in passing through metallic casing, is eliminated.

What I claim and desire to secure by Letters Patent is:

1. In a container of the class described, a tubular shell having open upper and lower ends, a closure member extending into the upper end, a closure member extending into the lower end, all of said members being of non-metallic material, and non-metallic means extending transversely through the shell and said closure members for securing the members to the shell.

2. In a container of the class described, a tubular shell having open ends, an upper link, a top closure member having a filler opening and longitudinal grooves terminating in transverse apertures for receiving said link, a lower link, a bottom closure member having a transverse opening for receiving the lower link, and means comprising a cross bar extending through the bottom closure member and having ends secured to the lower link for preventing pivotal movement of the lower link.

3. In a container of the class described, a tubular shell having open ends, an upper link, a top closure member having a filler opening and longitudinal grooves for receiving said link, a lower link, a bottom closure member having a transverse opening for receiving the lower link, means for preventing pivotal movement of the lower link, and non-metallic means extending through the shell and closure members for securing said members to the shell.

4. In a container of the class described, a cylindrical shell having upper and lower open ends, a bail, a closure member extending into the upper end having longitudinal grooves for receiving said bail and a stop shoulder for engaging the end of the shell, a hook, a hollow lower closure member extending into the lower end, having a stop shoulder for engaging the opposite end of the shell, means for attaching the hook to the closure member, and non-metallic means extending through the shell and closure members for securing said members to the shell.

In testimony whereof I affix my signature.

ALBERT G. STOOPS.
